UNITED STATES PATENT OFFICE.

HEINRICH SPÜHL, OF ST. GALLEN, SWITZERLAND.

APPARATUS FOR FACILITATING THE REMOVAL OF THE CONTENTS OF BOXES.

1,011,513.

Specification of Letters Patent.

Patented Dec. 12, 1911.

Application filed May 26, 1911. Serial No. 629,690.

To all whom it may concern:

Be it known that I, HEINRICH SPÜHL, a citizen of the Republic of Switzerland, residing at St. Gallen, in the Canton of St. Gallen, Republic of Switzerland, (whose post-office address is Rorschacherstrasse 75, St. Gallen,) have invented certain new and useful Apparatus for Facilitating the Removal of the Contents of Boxes; and I do hereby declare 10 the following to be a full, clear, and exact description of the invention, such as will enable others skilled in the art to which it appertains to make and use the same, reference being had to the accompanying drawings, and to letters of reference marked thereon, which form a part of this specification.

The improved apparatus has for its object 20 to facilitate the removal of the contents of a box, chest, or tin in shops, for instance a tin of biscuits, sweets, etc., so that it shall not be necessary for this purpose to shift the tins from their support on to the shop counter or to employ supports of inconvenient height in order to be able to remove 25 the contents from the tin with ease.

By means of the improved apparatus the tin is moved slightly and tilted somewhat forward, the lid is raised automatically during the tilting movement, the tin is held in the tilted position, and the lid is held in the opened position. In this position the contents can be removed wholly or partly with ease from the tin. By a gentle movement of 35 the hand the tin is tilted back into its original position, the lid closing automatically.

Two embodiments of this invention are illustrated by way of example in the accompanying drawings in which:

40 Figures 1, 2 and 3 are three side elevations of one construction of the improved apparatus for facilitating the removal of the contents of a tin, showing the apparatus in three different positions. Fig. 4 is a horizontal section on the line A—B of Fig. 1. Fig. 5 is an elevation of the apparatus with a section through one edge of the tin. Figs. 6 and 7 are respectively an enlarged elevation and an enlarged plan of a portion of 45 Figs. 1 and 4; Figs. 8 and 9 are respectively a side elevation and a plan of details, and Fig. 10 is a side elevation of a simplified construction of the improved apparatus.

50 A guide bar 4 (Figs. 1, 6, 7 and 9) is provided for each tin on the bottom 1 of the

support or frame 3 containing the tins 2 and is fixed by means of screws 5. The right hand side part of a rectangular supporting and tilting frame 7 (whose component parts are of L-section) rests on two feet 6 of the 60 guide bar 4.

The left hand side part of the frame 7 is supported on the bottom 1 of the frame 3 by means of a roller 8 fixed slightly in front of this side part, in such a manner that the 65 roller shall not leave the bottom of the frame 3 during the tilting movement. The frame 7 is intended to hold the tin 2.

The guide bar 4 is formed at its forward end, with a slotted eye 9 (Figs. 5 to 9) carrying a pin 12 on which a hand lever 10 having a gripping hole 11 is pivoted. An extension 13 of this lever extending at right angles therefrom carries a pin 14 and is connected by means of a connecting rod 15 to 75 a bar 16 parallel to the right hand side portion of the sliding frame 7 and attached thereto at its ends with interposed spacing pieces 17 and 18 (Fig. 8).

A vertical flat arm 19 (Figs. 1 and 4) is 80 clamped between the rear spacing piece 18 and the rear end of the bar 16. A similar arm 20 is attached to the rear end of the left hand side portion of the frame 7 (Figs. 4 and 5). A bent piece 22 (Figs. 1, 2, 3 and 85 5) is pivoted by means of pins 21 to the upper ends of the arms 19 and 20. The arms of this bent piece carry two rigidly fixed hooks 23 at their free ends. These hooks engage two oppositely situated side 90 edges of the lid 24 of the tin, which lid is pivoted on the axle α .

The arms of the bent piece 22 have a certain amount of resiliency relatively to each other so that the lid 24 is gripped with certainty. The right hand arm of the bent piece 22 (Figs. 3 and 5) is connected by means of a connecting rod 25 to a rocking arm 26 which is mounted rotatably on a pin 27 fixed to the bar 16. The rocking arm 26 is formed with an obtuse-angled longitudinal slot 28, 29, in which a pin 30 fixed to the guide 4 engages with a head 31 that prevents the arm 26 from slipping off the pin 30.

The guide 4 (Figs. 2, 3 and 6) has an 105 upwardly and forwardly inclined guide surface 32 for a pin 33 (Figs. 6 and 7) which extends across the space between the bar 16 and the right hand side part of the frame 7. The forward end of the guide surface 32 110

terminates in a recess 34 that serves as a "rest" for the pin 33. A tongue 35 extends from the guide 4 parallelly to the guide surface 32 so as to cover the upper portion of 5 the "rest" 34.

A shoulder 36 on the guide 4 serves as a stop for the spacing piece 17 (Fig. 6) when the frame moves back. A projection 37 of the guide 4, below which the bar 16 works, 10 holds the latter in its lowest position and prevents the forward portion of the frame 7 with the tin 2 from rising.

The operation of the apparatus is as follows: To remove the contents wholly or 15 partially from the tin 2, the hand lever 10 is rocked as indicated by the arrow I from the position shown in Fig. 1 into the position shown in Fig. 2, whereby the frame 7 with the tin 2 resting on it is pushed forward 20 from the position shown in Fig. 1 into the position shown in Fig. 2, and is tilted slightly on the axis of the antifriction roller 8 by the rising movement of the pin 33 along the inclined guide surface 32 of the guide 4. At the same time the arm 25 30 of the handlelever 10 in the direction of the arrow I (Fig. 1), the pin 33 slides completely up along the upwardly inclined guide surface 32 of the guide 4, whereby the frame 7 with the tin 2 is tilted fully on the axis of 35 the roller 8 into the position shown in Fig. 3. In this position the contents of the tin 2 are readily accessible. During the movement of the frame 7 and tin 2 from the position shown in Fig. 2 into the position shown 40 in Fig. 3, the longitudinal slot 28, 29 by sliding over the pin 30 has caused the rocking arm 26 to swing into its highest position and has thus opened the lid 24 completely. The tongue 35 of the guide 4 prevents a 45 premature tipping over of the frame 7 and tin 2. At the termination of the tilting movement the pin 33 drops into the "rest" 34 in the guide 4, and thus secures the frame 7 and tin 2 from tilting back and prevents 50 them from tipping over. The frame 7 is held sufficiently against lateral shifting by the support given to it by the guide 4 which projects between the bar 16 and the frame 7. When the desired portion of the contents 55 of the tin have been removed therefrom, the lever 10 is moved up again whereby the pin 33 is lifted out of the notch 34, the frame 7 with the tin 2 is first pushed back, and is then tilted back by the pin 33 sliding along 60 the guide surface 32. This tilting back is effected with very little exertion because the weight of the contents of the tin aids the backward tilting movement. During the latter part of the backward movement of 65 the frame 7 and tin, the pin 33 moves away

from the guide surface 32, and this part of the backward movement of the frame takes place in a straight line on the feet 6 of the guide piece. In the backward tilting of the frame 7 and tin 2 the rocking arm 26 moves 70 down again and thus closes the lid 24. Since only the lever 10 has to be operated, the contents of the tin can be removed very simply, easily and quickly.

In the simplified construction shown in 75 Fig. 10, the lever 10 and the rod 15 are dispensed with, and the front part 38 of the frame is provided with a handle or grip 39 for drawing the frame 7 and the tin 2 forward, tilting them and returning them into 80 their original positions. The most advantageous way as regards ease of manipulation is however to use the lever 10 and rod 15. The handle of grip 39 may have any desired form. The apparatus is also suitable for the 85 tins of round or other shape.

What I claim is:—

1. In apparatus for facilitating the removal of the contents of a tin or other box, the combination with a support, of a frame 90 for holding and tilting the tin, a handlelever pivoted to a fixed part, and connected to said frame, for moving said frame with the tin forward and backward, a fixed guide fixed to the support having an upwardly inclined guide surface, a pin on said frame movable along said guide surface for the purpose of tilting said frame forwardly, a rocking arm formed with an inclined slot, connected at one end to said frame and 95 adapted to be connected at its other end to the lid of the tin, and a pin on the support 100 engaging said inclined slot, whereby the lid of the tin can be opened and closed in a positive manner, as set forth.

2. In apparatus for facilitating the removal of the contents of a tin or other box, the combination with a support, of a frame for holding and tilting the tin, means for 105 tilting said frame into a desired position and maintaining the same therein, means for automatically opening the lid of the tin during the tilting of said frame and for maintaining said lid in the open position and a roller attached to said frame adapted to 110 bear always on the bottom of the support, serving as the axis of the tilting motion of said frame, as set forth.

3. In apparatus for facilitating the removal of the contents of a tin or other box, 115 the combination with a support, of a frame for holding and tilting the tin provided with arms, a bent piece pivoted to said arms, hooks on said bent piece for engaging the two side edges of the lid of the tin, a rocking arm pivoted to said frame formed with an inclined slot for positively opening and closing the lid of the tin, a guide pin fixed to the support engaging said inclined slot, a connecting rod connecting said bent piece to 120

105

110

115

120

125

130

said rocking arm, and means for tilting said frame into and maintaining same in any desired position, as set forth.

4. In apparatus for facilitating the removal of the contents of a tin or other box, the combination with a support, of a frame for holding and tilting the tin, a guide fixed to the support having an upwardly inclined guide surface for tilting said frame, a tongue on said guide for preventing the tipping over of said frame, a stop on said guide for limiting the backward movement of the said frame, and a projection on said guide for preventing the front part of said frame 10 from rising during the tilting movement, a rocking arm having an inclined slot pivoted to said frame, a guide pin fixed to said guide engaging said inclined slot, and means connecting said rocking arm to the lid of the tin in a freely movable and readily detachable manner, as set forth.

5. In apparatus for facilitating the removal of the contents of a tin or other box, the combination with a support, of a frame 25 for holding and tilting the tin, a bar fixed to said frame with interposed spacing pieces, a guide fixed to the support projecting between said frame and said bar having a forwardly and upwardly inclined surface for 30 guiding said frame, a hand lever pivoted to

the forward end of said guide, serving for moving said frame forward and backward, a connecting rod connecting said hand lever to said frame, and means connected to said frame for automatically opening and closing the lid of the tin during the tilting of said frame as set forth. 35

6. In apparatus for facilitating the removal of the contents of a tin, the combination with a support, of a frame for holding 40 and tilting the tin, a handle on said frame, a guide fixed to the support having a forwardly and upwardly inclined surface for raising the rear part of said frame and tin when said frame is drawn forward by means 45 of said handle, a guide pin fixed to said support, a rocking arm having an inclined slot, engaging said guide pin and connected to said frame and means connecting said rocking arm to the lid of the tin in a freely movable and readily detachable manner, as set forth. 50

In testimony whereof, I have signed my name to this specification in the presence of two subscribing witnesses.

HEINRICH SPÜHL.
